UNITED STATES PATENT OFFICE.

JOSEPH ALBERT BRIEGEL, OF CHICAGO, ILLINOIS.

DESIGN FOR A PIN OR BADGE.

47,990.

Specification for Design.

Patented Oct. 19, 1915.

Application filed August 30, 1915. Serial No. 48,117. Term of patent 14 years.

To all whom it may concern:

Be it known that I, JOSEPH ALBERT BRIEGEL, a citizen of the United States, residing at Chicago, in the county of Cook and State of Illinois, have invented a new, original, and ornamental Design for a Pin or Badge, as shown in the accompanying drawing, forming a part of this specification.

The figure is an elevation of a pin or badge showing my new design.

I claim—

The ornamental design for a pin or badge as shown.

In testimony whereof, I affix my signature.

JOSEPH ALBERT BRIEGEL.
